UNITED STATES PATENT OFFICE.

FRANK ROSEBROOK, OF ELMIRA, NEW YORK.

INCUBATOR.

SPECIFICATION forming part of Letters Patent No. 349,749, dated September 28, 1886

Application filed September 11, 1883. Serial No. 106,163. (No model.)

To all whom it may concern:

Be it known that I, FRANK ROSEBROOK, of Elmira, in the county of Chemung and State of New York, have invented a new and Improved Incubator, of which the following is a full, clear, and exact description.

The object of my invention is to provide a new and improved device for hatching eggs, and to provide for a perfect distribution of the heat in the incubator and other necessities for insuring a rapid and safe development of the embryos.

The invention consists in the peculiar construction and arrangement of parts, as hereinafter fully described, and pointed out in the claims.

Reference is to be had to the accompanying drawings, forming part of this specification, in which similar letters of reference indicate corresponding parts in all the figures.

Figure 1 is a longitudinal sectional elevation of my improved incubator on the line *zz*, Fig. 2. Fig. 2 is a plan view of the upper part of the boiler with the top plate removed. Fig. 3 is a cross-sectional elevation of the incubator on the line *xx*, Fig. 1. Fig. 4 is a sectional plan view of the same on the line *yy*, Fig. 1.

The incubator-casing, *A*, is made of wood with hollow walls, which may be lined with paper, felt, &c., or may be filled with some suitable non-conductor of heat. The casing is provided on two or on all sides with hinged or sliding doors, *A*², having glass panels, so that the interior of the casing can be seen plainly, and below the doors the casing is provided with longitudinal windows, *A*³, one end of each of which is open, but can be closed by means of a slide, *A*⁴. These openings are provided for the purpose of admitting fresh air into the incubator. Cleats *B* are hung on pins *B*' on the inner sides of the casing *A* by means of hangers *B*² in such a manner that the said cleats will be slightly inclined from the sides toward the middle longitudinal partition, *C*, of the casing. To permit of adjusting the cleats higher or lower the hangers *B*² are provided with two or more apertures, through which the pins *B*' can be passed. The egg-carrying drawers or trays *D* rest and slide on these cleats *B*, and consist of a frame, *C*', with a wire-netting or perforated or slatted bottom, *C*², which is divided into a series of compart-

ments or spaces by longitudinal strips *C*, extending longitudinally of and having their ends secured to the frame, each compartment 55 or subdivision being of such size as to receive one row of eggs. The egg-drawers *D* are so located that they can be passed into the casing *A* when the doors *A*² are opened.

The hot-water tank consists of a flat vessel, *E*, resting on the upper part of the casing *A*, and subdivided, by longitudinal and transverse partitions *E*' *E*², into a series of channels, in which the hot water circulates in a manner that will be fully described and set forth hereinafter.

The tank *E* is provided with an opening, *D*', for the ventilation-flue, in which a damper-valve, *J*, is provided. By means of a tube, *E*³, the flat tank *E* is connected with the top 70 of an upright cylindrical vessel or boiler, *F*, provided with a longitudinal conical flue, *F*', below which a lamp, *G*, a gas-burner or other suitable source of heat, rests upon a bracket, *G*'. A pipe, *F*², leads from the lower part of 75 the cylindrical vessel *F* to a serpentine water-pipe, *F*³, in the casing *A*, which pipe is connected at the opposite end with the flat tank or vessel *E* by means of pipes *F*⁴, so that the hot water can circulate in the vessel *E*, the 80 pipe *E*³, the vessel *F*, and the pipes *F*², *F*³, and *F*⁴, whereby a very large radiating surface is obtained, and the air in the casing *A* will be heated thoroughly and uniformly. Flat vessels *H*, containing water, are placed upon 85 the serpentine pipes *F*³, so that the water in these vessels will be evaporated, thus producing the moisture required.

The space below the serpentine pipes *F*³ in the casing is to be used as a temporary nursery 90 for the young chickens. The hot water rises in the boiler *F* and circulates through the pipe *E*³ and passes into the vessel *E*. It then passes into the outer channels of the same, and thus heats the casing at the sides and ends, where 95 it is most exposed to the cold surrounding air. It then passes through the inner channels, and then through the pipes *F*⁴ and the serpentine pipes *F*³ back to the boiler *F*'. The air in the casing is thus heated uniformly and most 100 where the most heat is required—that is, at the sides which have glass doors—and thus are colder than the interior part of the casing.

It is of great importance to be able to watch

the interior of the casing without opening the door every time the progress is to be observed. This is only possible if the casing is provided with the glass doors, or, if desired, with fixed 5 glass panels, glass doors being preferred.

By means of the hangers B² the trays can be adjusted to a greater or less distance from the bottom of the vessel E, and can thus be exposed to more or less heat radiated from the 10 bottom of the vessel E, accordingly as may be necessary.

I make no claim in this application to the egg-tray shown and described, as it forms the subject-matter of my application, filed May 15 26, 1885, and patented August 11, 1885, No. 324,274.

Having thus described my invention, what I claim as new, and desire to secure by Letters Patent, is—

20 1. In an incubator, the combination, with a boiler, of a hot-water tank located above the egg-chamber and divided by partitions into channels for conducting the water first to both sides of the tank and then toward the middle

25 of the same, and communicating with the upper and lower portions of the said boiler by means substantially as shown and described.

2. In an incubator, the combination, with the boiler, of a hot-water tank divided by partitions into channels that conduct the water first to the outside of the tank, then back to the center, and of a system of pipes connected with said hot-water tank and with the boiler for the purpose of conducting the water from said tank back to the boiler, substantially as 30 herein shown and described.

3. In an incubator, the combination, with a boiler, of a hot-water tank divided by partitions into channels that conduct the water first to the outside of the tank, then back to the 40 center, a system of pipes connected with said hot-water tank and with the boiler for the purpose of conducting the water from said tank back to the boiler, and water-pans resting upon said pipes, substantially as herein 45 shown and described.

4. The combination, with the trays C², of the hangers B², provided with a series of apertures, and of the pins B, substantially as herein shown and described.

FRANK ROSEBROOK.
